UNITED STATES PATENT OFFICE.

RICHARD G. EVANS, OF PITTSBURG, PENNSYLVANIA, ASSIGNOR TO H. J. HEINZ CO., OF PITTSBURG, PENNSYLVANIA, A COPARTNERSHIP.

DESIGN FOR A BOTTLE.

SPECIFICATION forming part of Design No. 37,226, dated November 15, 1904.

Application filed July 21, 1904. Serial No. 217,533. Term of patent 14 years.

To all whom it may concern:

Be it known that I, RICHARD G. EVANS, a citizen of the United States, residing at Pittsburgh, in the county of Allegheny and State 5 of Pennsylvania, have invented a new, original, and ornamental Design for a Bottle.

Said design is illustrated in the accompanying drawings, in which—

I claim as new and desire to secure by Letters Patent—

The ornamental design for a bottle, substantially as shown.

RICHARD G. EVANS.
